CLAIM

The ornamental design for a multiport closure, as shown and described.

DESCRIPTION

FIGS. 1-4 are isometric views of a multiport closure, illustrating an embodiment of our new design;

FIG. 5 is a front view thereof;

FIG. 6 is a rear view thereof;

FIG. 7 is a left view thereof;

FIG. 8 is a right view thereof;

FIG. 9 is a top view thereof; and,

FIG. 10 is a bottom view thereof.

(Continued)

The broken lines in the drawings depict portion of the multiport closure that form no part of the claimed design.

1 Claim, 10 Drawing Sheets
